UNITED STATES PATENT OFFICE.

WALTER J. BARRON, OF NEW YORK, N. Y., ASSIGNOR, BY MESNE ASSIGNMENTS, TO UNION TYPEWRITER COMPANY, OF JERSEY CITY, NEW JERSEY, A CORPORATION OF NEW JERSEY.

TYPE-WRITING MACHINE.

1,023,796.

Specification of Letters Patent. Patented Apr. 23, 1912.

Application filed August 19, 1910. Serial No. 577,957.

To all whom it may concern:

Be it known that I, WALTER J. BARRON, citizen of the United States, and resident of the borough of Brooklyn, city of New York, in the county of Kings and State of New York, have invented certain new and useful Improvements in Type-Writing Machines, of which the following is a specification.

10 My invention relates to indicating mechanism and type bar repulser mechanism for typewriting machines.

One object of my invention is to provide improved indicating devices for indicating the printing point on the platen, said devices being simple in character and near the printing point so that a close adjustment may be obtained of any desired point on the work sheet to the printing point.

20 Another object of the invention is to provide improved repulser devices for coöperating with the type bars when actuated to facilitate their return from printing to normal position.

25 A third object of the invention is to provide devices which combine the functions of a printing point indicator and type bar repulser.

To the above and other ends my invention consists in the features of construction, combinations of devices and arrangements of parts to be hereinafter described and particularly pointed out in the claims.

My invention is shown as applied to a No. 35 10 Remington typewriting machine but the nature of said invention is such that it may readily be adapted to other styles of writing machines.

35 In the accompanying drawings illustrating one form of my invention, Figure 1 is a fragmentary vertical front to rear sectional view of a No. 10 Remington machine embodying my invention, parts of said machine being omitted and parts broken away.

45 Fig. 2 is a fragmentary vertical transverse sectional view of some of the parts shown in Fig. 1 but showing one of the type bars in printing position. Fig. 3 is a fragmentary front elevation of some of the parts shown 50 in Fig. 2. Fig. 4 is a fragmentary front view on an enlarged scale showing the relationship between the indicating device and the printing point in the shifted position of the platen.

55 As shown in Fig. 1 the main frame of the

machine comprises a base portion 1 from which rise posts 2 supporting a top plate 3. Key levers 4 are fulcrumed on a plate 5, each key lever being connected by a link 6, lever 7 and second link 8 to a type bar 9. 60 The type bars are pivoted at 10 to hangers secured to a stationary support 11. The free ends of the type bars normally rest on a stationary support 12. Each type bar carries a type block 13 which is provided 65 with two types 14 and 15, the former being a small and the latter a capital letter. Between the types on each type block is a depression or space 16, the bottom of which is the face of the block proper. 70

When the type bars are actuated the types are adapted to coöperate with the front face of a roller platen 17 pivotally supported on a platen frame comprising end bars 18 and a cross bar 19, said frame being connected by 75 links or devices 20 to a carriage or truck comprising end bars 21 and front and rear bars 22. The bars 22 are oppositely grooved to receive anti-friction balls 23 which also coöperate with fixed guide rails 24. The 80 truck and platen frame compose a carriage for the platen, which carriage is impelled leftward by the usual spring drum (not shown), the leftward or printing movements being controlled by escapement devices of the usual or any suitable pattern 85 which are connected by a link 25 with an arm 26 fixed to a rock shaft 27 mounted in the base 1. Fixed to said rock shaft near its ends are arms 28 from which depend arms 28^a, said arms carrying a universal bar 29 which underlies the key levers 4 and is adapted to be actuated to operate the escapement when any key lever is suitably depressed. 90

Independently of its letter spacing movements with the carriage, the platen and platen frame are adapted to be shifted on the truck in order to change case. The platen carrier or frame carries a wheel or roller 30 which runs on a shift rail 31, said shift rail being comprised in a shiftable frame which further includes upright side bars or rods 32 and a rectangular cross bar 33 from which extend downward arms 34. 100 Pivoted at 35 to each arm 34 is a shift lever 36 fulcrumed at 37 and provided with a shift key 38 operative when depressed to lift the shift frame and elevate the platen frame and platen to receive imprints from 105 110

the upper case types, 15. The mechanism above described is common to the No. 10 Remington machine and need not be set forth at greater length.

5 Secured centrally to the shift rail 31 by screws 39 is a bracket 40 which carries a combined card guide and line indicator 41, the latter comprising downwardly extending flexible arms 42 which are secured to the bracket 40 by screws 43. The member 41 was not invented by me nor was the support thereof, and neither is claimed *per se* by me herein. The combined indicating device and repulser wherein my invention 10 more especially resides is made preferably of spring wire and as shown clearly in Figs. 2 and 3 comprises an upright portion 44 having an angularly disposed inwardly bent portion 45 at the upper end, the lower end of the upright portion 44 terminating in a loop 46. The loop 46 receives a headed screw 47 which engages a tapped hole in the member 41 at the top of the right-hand arm 42 and detachably secures the indicating device to its support. The arm or portion 44 extends upward transversely of the printing line (represented in Fig. 2 by the letters *l*, *n*) and is offset or bent rearward above the screw 47 so as to lie close to the face of the card guide, but the portion 45 is clear of the card guide, so that nothing is interposed between 45 and the platen save the paper. The portion 45 extends lengthwise of the platen and of the printing line and above said printing line, terminating over the printing point but in line therewith. In other words, the inner or left-hand end or edge of the part 45 is directly over the middle of the small letter *n*, which as shown is overlying the printing point so that a line transverse of the printing line and at right angles thereto and passing through the printing point will also contain the end or edge of the portion 45. Such a line is the broken line in Fig. 3 designated by the reference numeral 48. The letter *h* in Fig. 3 is in the line above the printing line. It will be observed that the pointer is close to and in the same vertical line as the printing point, so that any desired portion of the work sheet may be readily brought to the printing point because of the facility with which the printing point may be located by means of the pointer. It will further be observed that the pointer or indicating device is on a relatively stationary part of the machine which does not move during printing operations. Furthermore, the pointer is on a support which shifts with the platen so that the pointer always bears the same normal relationship with the platen in uppercase as well as in lowercase. This will be understood more especially from Fig. 4 which shows the indicating device or pointer in

shifted position with the capital letter *N* overlying the printing point.

The indicating device or finger is preferably made of spring metal as above stated and the horizontal portion 45 normally stands slightly away from the printing face of the platen as shown in Fig. 1. This portion is so located that when a type bar is actuated the types 14 and 15 thereon will pass at opposite sides above and below the portion 45 which will engage the space or opening 16 between and separating said types. Just prior to the printing moment the face of the type block 13 between the types will engage the portion 45 and will force it toward the platen to the position shown in Fig. 2, thereby flexing somewhat the inner or free portion of the arm 45, the opposite end of which will be forcibly pressed against the card guide. Consequently when the actuated key lever is released the spring in the arm or portion 45 of the indicating device serves to assist the key lever spring 49 in restoring the type bar to normal position, the type bar receiving its initial impulse away from the platen from the indicating device which thus serves as a repulser.

It will be observed that the repulser operates with the type bar at the farthest practicable point from the pivot thereof, which is the most effective point for co-operation. In other words, a slight impulse communicated to the outer end of the type bar will be more effective than a considerably greater impulse communicated near the type bar pivot would be.

It will be noted further that the detachable spring finger herein described is simple and inexpensive in construction, may be applied without altering the machine in any respect, and provides an effective pointer or indicator for the printing point on the platen and also an effective repulser for the type bars, preventing blurring and promoting the speed of the type bars at the start of their return movements.

Various changes may be made without departing from the scope of my invention.

What I claim as new and desire to secure by Letters Patent, is:

1. In a typewriting machine, the combination with a platen, of an indicating device extending lengthwise of the printing line and terminating above the printing point and in the line which contains the printing point and extends at right angles to the printing line, said device remaining constantly in indicating position.

2. In a typewriting machine, the combination with a platen, of an indicating device extending lengthwise of the printing line and above the same and terminating above the printing point in the same transverse line as the printing point, said trans-

verse line being at right angles to the printing line, said device remaining constantly in indicating position.

3. In a typewriting machine, the combination with a platen, of an angular indicating device having a portion extending transversely of the printing line at one side of the printing point and having another portion extending lengthwise of the printing line and terminating in a line which contains the printing point and is at right angles to the printing line, said device remaining constantly in indicating position.

4. In a typewriting machine, the combination with a platen, of an angular indicating device having a portion extending transversely of the printing line at one side of the printing point and having another portion extending lengthwise of the printing line and above the same and terminating in the same vertical line as the printing point, said device remaining constantly in indicating position.

5. In a typewriting machine, the combination of a platen, key controlled type bars, each type bar comprising a type block carrying a plurality of types, and an indicating device having a portion extending lengthwise of the platen and adapted at the printing moment to fit in the space between two types on the type block of the actuated type bar.

6. In a typewriting machine, the combination with a shiftable platen, of an indicating device shiftable with said platen so as to occupy always the same normal relationship with respect to said platen, said indicating device extending lengthwise of the printing line on the platen and terminating in the same transverse line as the printing point, said transverse line extending at right angles to the printing line.

7. In a typewriting machine, the combination with a shiftable platen, of an indicating device shiftable with said platen so as to occupy always the same normal relationship with respect to said platen, said indicating device extending lengthwise of the printing line and above the same and terminating above the printing point in the same transverse line as the printing point, said transverse line being at right angles to the printing line.

8. In a front-strike typewriting machine, the combination with a shiftable platen, of an indicating device shiftable with said platen so as always to occupy the same nor-

mal relationship with respect to said platen, said indicating device extending lengthwise of the printing line and terminating in a vertical line which passes through the printing point.

9. In a typewriting machine, the combination with a shiftable platen, of an indicating device shiftable with said platen, said indicating device having angularly disposed portions, one portion extending transversely of the printing line at one side of the printing point and another portion extending lengthwise of the printing line and above the same and terminating in the same vertical line as the printing point.

10. In a typewriting machine, the combination with a shiftable platen, of a key controlled shift rail, and a pointer secured to said shift rail and comprising a portion extending transversely of the printing line at one side of the printing point and another portion extending lengthwise of the printing line and terminating above the printing point.

11. In a typewriting machine, the combination with a platen, and key controlled type bars, of a spring pointer for indicating the printing point, said pointer acting as a repulser for the type bars.

12. In a typewriting machine, the combination of a platen, key controlled type bars each carrying a type block, and a repulser coöperative with the type blocks, said repulser also acting as a printing point indicator.

13. In a typewriting machine, the combination of a platen, key actuated type bars each comprising a type block carrying two types, and a spring finger coöperating with the actuated type bar, said finger co-acting at the printing moment directly with the type block between the two types thereon, said finger also coöperating with the platen to indicate the printing point.

14. In a typewriting machine, the combination of a shiftable platen, key controlled type bars, and a repulser for said type bars, said repulser being shiftable with said platen.

Signed at Hingham, in the county of Plymouth, and State of Massachusetts, this 17th day of August, A. D. 1910.
